UNITED STATES PATENT OFFICE.

GEORGE W. SANBORN AND JOSEPH C. SANBORN, OF UTICA, NEW YORK.

DESIGN FOR A CLOTHES-LINE POST.

SPECIFICATION forming part of Design No. 29,940, dated January 3, 1899.

Application filed September 2, 1897. Serial No. 650,402. Term of patent 3½ years.

To all whom it may concern:

Be it known that we, GEORGE W. SANBORN and JOSEPH C. SANBORN, residents of the city of Utica, in the county of Oneida and State of New York, have invented and produced a new and original Design for Clothes-Line Posts, of which the following is a specification, reference being had to the accompanying drawings, forming a part hereof.

Figure 1 is a side elevation of our design for posts. Fig. 2 is an edge view. Fig. 3 shows the opposite side from that shown in Fig. 1. Fig. 4 is a perspective view.

The feature of our design is the form and configuration of the article as a whole, as

shown in the drawings, the component parts of which may be specified as follows: the round post 1, cross-tree 2, with its mountings 3, the disk 4, with its mountings surmounting the post, and flanged base-piece 5, adjacent to the lower end of the post.

What we claim as new is—

The design for a clothes-line post as herein shown and described.

GEORGE W. SANBORN.
JOSEPH C. SANBORN.
